UNITED STATES PATENT OFFICE.

HENRY BRUNT, OF BALTIMORE, MARYLAND.

DESIGN FOR A PITCHER.

SPECIFICATION forming part of Design No. 32,473, dated April 10, 1900.

Application filed February 14, 1900. Serial No. 5,229. Term of patent 3½ years.

To all whom it may concern:

Be it known that I, HENRY BRUNT, a citizen of the United States, residing at Baltimore, in the State of Maryland, have invented and produced a new and original Design for Pitchers, of which the following is a specification.

The accompanying drawing illustrates a pitcher having my ornamental design.

The ornamental design is applied to the swell or large part of a pitcher, ewer, or jug; and it consists of two scrolls, whose small lower ends adjoin each other and the large ends, projecting in opposite directions, turn upward, with an ornamental bouquet of flowers filling and extending above said larger

turned-up ends. The scrolls have a trumpet-like form. At the right and above one of said trumpet scrolls is a vase-shaped ornament, also containing flowers, and at the top and in the center are a large rose and a small bud, 20 and from which depend sprigs of small flowers.

What I claim is—

The design for a pitcher, ewer or jug, substantially as shown and described.

In testimony whereof I affix my signature 25 in the presence of two witnesses.

HENRY BRUNT.
